UNITED STATES PATENT OFFICE.

HARRY H. BROWN, OF YORKVILLE, SOUTH CAROLINA; JOSEPH G. SASSI ADMINISTRATOR OF SAID BROWN, DECEASED.

FIRE-ALARM.

1,178,379.

Specification of Letters Patent.

Patented Apr. 4, 1916.

Application filed May 14, 1914. Serial No. 838,528.

To all whom it may concern:

Be it known that I, HARRY H. BROWN, a citizen of the United States, residing at Yorkville, in the county of York and State 5 of South Carolina, have invented certain new and useful Improvements in Fire-Alarms, of which the following is a specification.

This invention relates to fire alarms, and 10 the primary object of the invention is the provision of a fire alarm as specified, which is operable upon the breaking out of fire in any part of a building, for sounding an alarm and acquainting persons of the existence of the fire.

Another object of this invention is the provision of a novel type of governing mechanism for controlling the operation of the signal sounding mechanism.

20 With the foregoing and other objects in view, this invention consists in such novel features of construction, combination, and arrangement of parts as will be hereinafter more fully described, illustrated in the accompanying drawings, and claimed.

In describing the invention in detail, reference will be had to the accompanying drawings, wherein like characters designate like or corresponding parts throughout the 30 several views, and in which:—

Figure 1 is a central sectional view through the supporting casing of the improved fire alarm, exposing the internal operating mechanism thereof, Fig. 2 is a cross sectional view taken on the line 2—2 of Fig. 1 and looking in the direction indicated by the arrow *a*, Fig. 3 is a fragmentary cross sectional view taken on the line 2—2 of Fig. 1 looking in the direction indicated by the arrow *b*, Fig. 4 is a cross sectional view on the line 4—4 of Fig. 1, and Fig. 5 is a detail view of the governing mechanism employed for regulating the speed of the signal sounding mechanism.

45 Referring more particularly to the drawings, 1 designates the protective casing of the fire alarm, which casing has a shaft 2 journaled transversely thereacross, which shaft has a coil spring 3 mounted upon one 50 end thereof. The coil spring 3 is connected to the shaft 2 in such a manner that when the shaft is manually rotated by the handle 4 thereupon, the spring will be wound. The shaft 2 has a gear 5 mounted thereupon,

which gear meshes with the pinion 6. The 55 pinion 6 is carried by the shaft 7, which shaft is journaled transversely across the supporting casing 1, and has its terminal ends seated in brackets 8, which are secured to the opposite sides of the supporting casing. 60 The shaft 7 has a crank portion 9 formed therein, which crank portion has a connecting rod 10 connected to its vertex. The connecting rod 10 is also connected to the crank handle 11 of the shaft 12. The shaft 65 12 is supported within the casing 1 by brackets 13 and 14, the bracket 14 being suspended from the upper wall of the casing 1. The shaft 12 has a bell clapper 15 secured thereto, which bell clapper projects 70 out of the uppermost side of the casing and is adapted for striking engagement against the bell 16, for sounding an alarm.

A bracket 17 is secured to one side of the casing 1, and it has a lever 18 pivotally 75 mounted upon its outer terminal end, which lever has one end positioned for engagement with the teeth formed upon the periphery of the gear 5 for restraining the gear 5 from rotation. The lever 18 has a spring 19 connected to its upper end, which spring is secured to the bracket 17, and tends to hold the end of the lever out of engagement with the peripheral teeth of the gear 5. A cord 20 is secured to the opposite end of the lever 80 85 18 from the end which engages the teeth of the gear 5 and extends out through the casing and is positioned about various rooms of a house. The cord 20 is formed of any suitable type of material which is fusible by 90 heat, so that when a fire breaks out in the house the cord will be severed or melted by the heat, and this will release the lever 18 from restraint, permitting the spring 19 to move the lever upon its pivotal point and 95 out of engagement with the teeth of the gear, which will permit the gear 5 to be rotated by the unwinding action of the coil spring 3. When the gear 5 is rotated by the unwinding of the coil spring 3, the rotation thereof will be imparted to the shaft 7 through the meshing engagement of the gear with the pinion 6. The rotary motion of the shaft 7 will be imparted to the shaft 12 in a vibratory or oscillatory manner, 100 through the connection of the connecting rod 10 and the crank portions 9 and 11, 105 which motion will cause the clapper arm 15

to vibrate against the sides of the bell 15 for sounding an alarm.

The cord 20 has springs 21 interposed therein, which springs will take up the slack in the cord, holding it taut at all times so that it will properly hold the lever 18 positioned for engagement with the teeth of the gear 5 except when the cord is severed by a fire.

10 The shaft 12 has a governing arm 22 mounted thereupon, which governing arm has a balancing ball 23 positioned upon one end and a pair of transversely extending friction shoes 24 and 25 formed upon the 15 other end, which shoes are positioned diametrically opposite to each other about the periphery of the friction drum 26, which is mounted upon the shaft 7. Upon the vibratory or oscillatory movement of the shaft 12, 20 the governor 22 will be oscillated, causing the brake shoes 24 and 25 to intermittently engage the periphery of the friction drum or wheel 26, thereby retarding the rotation of the shaft 7 and the unwinding of the 25 spring 3 for increasing the length of time of the sounding of the alarm.

From the foregoing description, taken in connection with the accompanying drawings, the advantages of the construction and 30 of the method of operation of the improved fire alarm will be readily apparent to those skilled in the art to which this invention appertains, and, while in the foregoing the principle of the operation has been described, together with various features of 35 construction, it is to be understood that certain minor features of construction, combination, and arrangement of parts may be altered to suit practical conditions, provided

such alterations are comprehended within 40 the scope of what is claimed.

What is claimed is:—

In a fire alarm, a casing, a shaft journaled transversely through the casing at its lower end, a coil spring at one end of said shaft, 45 means for rotating the shaft at its opposite end, a gear wheel mounted on said shaft and disposed within the casing, a second shaft journaled within the casing, a pinion at one end of said second shaft, a crank portion formed at the opposite end of the second shaft, said pinion meshing with the gear carried by the first mentioned shaft, a third shaft journaled in the upper portion of said casing and connected to the second shaft by 50 a connecting rod at its outer end, the free end of the connecting rod secured to the crank portion of the second shaft, a friction drum centrally mounted on the second shaft, and means mounted on the third shaft for 55 engaging the friction drum to regulate the speed of rotation of the same, a bell clapper secured to the third shaft and extending upwardly through the top of the casing, a bell over said bell clapper, means in the lower 60 portion of the casing adapted to engage the teeth of the gear of the first mentioned shaft to prevent the same from rotating, a flexible means connected to the first mentioned 65 means for holding the same in engagement with said teeth for preventing the same from rotating.

In testimony whereof I affix my signature in presence of two witnesses.

HARRY H. BROWN.
